UNITED STATES PATENT OFFICE.

MAURICE J. WRIGHT, OF BOISE, IDAHO.

REGISTER DUST COVER.

Application filed June 22, 1923. Serial No. 647,073.

My invention relates to register dust covers, and particularly to a device of this character intended for use with hot-air heating registers, to catch the dust usually thrown off by such registers due to the circulation of the heated air.

An object of this invention is to provide a cover which can be readily and expeditiously fitted for use upon any and all hot air registers as the same are installed in accordance with standard installation practices, and which will strain all air emanating from the register.

A further object resides in so constructing the cover and the dust-collecting portion that the entire structure can be readily washed or otherwise cleaned when occasion demands.

A still further object is to provide for moistening the heated air passing from the register, where this is deemed desirable.

With the above and other objects in view, which will be apparent to those skilled in the art, this invention includes certain novel features of construction and combinations of parts which will now be set forth in connection with the drawings.

In the drawings:

Figure 1 is a broken sectional view through a hot-air register and pipe installation, showing my invention applied thereto.

Fig. 2 is a perspective view of the register cover.

Fig. 3 is a perspective view showing the supporting frame and the fabric retaining ring.

Fig. 4 is a fragmentary perspective view illustrating detailed construction.

In the showing in Fig. 1, the supporting rim 1, for the register 2, is installed through the floor 3 in the usual manner, the hot air pipe 4 being connected with the usual register box 5. The register 2 has a supporting frame and bearing portion 6 depending therefrom to carry the usual leaves or louvres 7, and in all respects the register fitting and connections are a standard installation.

My improved dust cover can be applied for use either within the register box 5 or over the register 2, and in the present instance, I have shown the fitting within the box 5, this being accomplished by lifting the register 2 from the frame 1, placing the cover on the bottom of the box 1 over the outlet opening of air pipe 4, and replacing the register.

The cover consists essentially of a skeleton

frame 8, made up of wire or other suitable material bent to the desired shape and secured in any desired manner, which frame is of rectangular shape in plan, or is of any other shape to fit within the register box 5, or over the register 2. The essential feature in the shape and size of this skeleton frame is that it must completely cover all openings of the register 2, or must completely cover the opening from the hot air pipe. The frame has a rim portion 9, and upright portions 10, which carry supporting top bars 11, and a retaining ring 12 is made of substantially the same general shape as the rim 9 and of sufficient size to fit loosely down over the top bars and the uprights, to come against the rim ring 9.

This supporting frame structure is adapted to be covered with a piece of burlap or other coarse and more or less open fabric 13, this fabric being brought down over the sides of the frame and being held in place at its edges by the retaining ring 12, after the manner shown in Fig. 2.

The dust cover, with the parts assembled, as best shown in Fig. 2, is placed within the register box 5 after the manner illustrated in Fig. 1, or can be fitted in place over the register 2. In this mounting, the heated air must pass through the fabric covering 13, and in consequence the air will be strained and dust and smoke particles will be removed. When the fabric covering 13 is soiled, it can be removed and washed or otherwise cleaned to be replaced, or a new covering can be used. The retaining ring 12 holds the fabric covering against the rim portion 9 of the supporting frame, and this covering is thus retained in a proper dust-collecting position.

As best shown in Fig. 4, I have mounted a spout or trough 14 around the supporting frame to be disposed adjacent the rim 9, this trough or spout being adapted to contain water. With this form of cover, when the fabric is fitted in place and the trough 14 is filled with water, the water will be taken up by capillary attraction to moisten the covering, and as the heated air passes through the fabric, this water will be evaporated off to moisten the air.

While in the foregoing I have shown and described only certain specific embodiments and have set forth certain specific manners of applying the dust cover for use, it will be appreciated that other changes and variations

can be resorted to without departing from the spirit and scope of my invention.

I claim:

5 A register dust cover for use in conjunction with a hot air register comprising a skeleton frame to be fitted in the path of air passing from the register, a water trough extending entirely around the lower edge of

said frame, a fabric covering to be removably fitted upon the frame to cover all portions thereof, and a ring to be fitted down over the sides of the frame to secure the fabric in place thereon and to hold the same with its edges in the water trough.

In testimony whereof I affix my signature.

MAURICE J. WRIGHT.
